UNITED STATES PATENT OFFICE.

THOMAS A. BELL, OF PARKVILLE, NEAR MELBOURNE, VICTORIA, AUSTRALIA.

STARTING OF HIGH-COMPRESSION OIL ENGINES.

Application filed September 4, 1923. Serial No. 660,882.

To all whom it may concern:

Be it known that I, THOMAS ANDREW BELL, a subject of the King of Great Britain and Ireland, and a resident of the postal 5 district of Parkville, a suburb of the city of Melbourne, in the county of Bourke, State of Victoria, Commonwealth of Australia (whose post-office address is 19 Park Street, in the said postal district of Parkville), have 10 invented certain new and useful Improvements Relating to the Starting of High-Compression Oil Engines, of which the following is a specification.

This invention relates to internal combustion oil engines of the relatively high compression type such as those working on the "Diesel" or "semi-Diesel" principle in which during normal working combustion is effected wholly or partially by the heat of 20 compression. More particularly the invention refers to the starting of such engines to initiate the necessary heat of compression for normal working.

Apart from low powered engines which 25 may be started by hand, it is the general practice to start oil engines of the kind indicated by means of compressed air and to change over to the normal working cycle when the necessary compression is obtained 30 in the engine cylinder. This requires a special air compressor or starting reservoir which considerably increases the cost and complexity of the apparatus.

In starting, relatively low compression oil 35 engines such for instance as the type commonly known as kerosene engines, carburetted air fuel is frequently employed the heavier oil fuel being subsequently introduced and vaporized by contact with a heated surface, in the combustion chamber.

Such engines do not however rely upon the heat of compression to effect combustion and owing to the relatively low compression no danger is involved in firing the carburetted starting charge at full compression 45 as would be the case with relatively high compression engines.

The present invention aims at starting oil engines of the relatively high compression 50 type with carburetted fuel and spark ignition and to this end it is necessary that the compression in the engine cylinder should be reduced to a sufficient degree during starting operations to permit of the safe firing of the compressed charge from the carburettor.

The chief characteristic of the present invention consequently resides in discharging portion of the carburetted starting charge of mixture during the compression stroke of 60 the piston during starting operations so that the degree of compression is thus reduced and the carburetted charge may be fired without danger.

This release of part of the starting charge is preferably effected by automatically opening the exhaust valve during the compression stroke as well as during the exhaust stroke, and such additional opening of the exhaust valve is conveniently effected 65 by the provision of an auxiliary cam which is employed only during starting operations and is moved out of operative position when it is desired to change over from the starting cycle to the normal working cycle where- 70 in the cylinder must be closed during the compression stroke.

A further important feature of the invention resides in the provision of a safety device whereby the shifting of the aforesaid cam to discontinue the opening of the exhaust valve during compression cannot be effected until the carburettor, which supplies the starting charge, has been cut off from the cylinder and the latter has been opened 80 to the atmosphere to draw in the usual fresh air charge for normal working. It is thus impossible to manipulate the parts to obtain full compression while the engine is operating on the carburettor, such full compression 85 being obtained only when the carburettor is cut off and the parts are in position to admit fresh air during the suction stroke.

Consequently no danger of firing the carburetted starting charge at excessive pressure is incurred.

Further features of the invention will be evident from the following description and appended claims.

Referring to the drawings which form 100 part of this specification:—

Figure 1 is a part sectional side elevation of apparatus in accordance with the invention the parts being shown in position for starting.

Figure 2 is a part sectional plan of portion of Figure 1.

Figure 3 is an end view looking in the direction of the arrow A Figure 1.

Figure 4 is a sectional detail view on an 110 enlarged scale of a fuel control valve, by which gas from the carburettor is admitted

to the engine cylinder during starting and atmospheric air during normal running.

Figure 5 is a part sectional plan of Figure 4, and also shows certain of the operative connections whereby manipulation of the fuel control valve to cut out the carburettor simultaneously releases a hand lever by movement of which full compression is obtained.

10 Figure 6 is a plan view of said hand lever and a slotted locking plate carried thereby.

Referring to the drawings the numeral 2 indicates the engine cylinder into the combustion chamber of which carburetted fuel 15 or atmospheric air is admitted by manipulation of a fuel control valve illustrated in Figures 1 to 5. This valve preferably includes a hollow casing 3 which may be secured in suitable position on the cylinder 20 head as shown, the valve casing being provided with a gas inlet branch 7 adapted to receive an induction pipe 8 leading from a carburettor 9. The valve casing 3 also has an air inlet port 11 open to the atmosphere.

25 Rotatably accommodated within the valve casing 3 is a rotary sleeve valve 12, closed at its upper end and opening at its bottom into the engine cylinder. In the wall of this valve are ports 13 and 14 adapted to coincide 30 with the aforesaid gas inlet branch 7 and the air inlet port 11 respectively. When starting the engine this fuel control valve is in the position shown in Figures 4 and 5 so that port 13 registers with the gas inlet branch 7 communicating with the carburettor, while the air inlet port 11 of the valve casing is closed by the vertical wall of the rotary sleeve. When the engine is running on its normal cycle the gas inlet branch 7 is 35 cut off from the interior of the valve casing and the port 14 in sleeve registers with the air inlet port 11. Atmospheric air instead of gas from the carburettor is thus drawn into the cylinder 2 on the suction stroke of 40 the piston.

45 Seating within a port 15 at the bottom of the valve casing 3 is the usual inlet valve 16 of the poppet type which controls the admission of the carburetted gas or the atmospheric air as the case may be from the interior of the valve casing 3 to the engine cylinder 2. The stem 17 of this inlet valve 50 16 may pass through a guide bearing 18 and protrudes upwardly beyond the closed end 55 of the rotary sleeve 12 where the usual spring 19 is provided to normally retain the head of the valve 16 tightly against its seating. Said inlet valve 16 may be actuated to open during the suction stroke of 60 the piston by means of the usual rocker arm 22 which is intermediately pivoted to a lug or lugs 23 on the valve casing 3, and connected to a tappet rod 24 actuated by a cam 26 on the cam shaft 27 the latter being 65 driven in the usual manner from the main

crank shaft 28 by gears 29 or other suitable means.

Attached to a projection 32 on the rotary valve 12 is a link 31 which is flexibly connected as by a ball and socket joint 33 to one end of a connecting rod 34 the other end of which may be provided with a similar flexible connection 35 to one arm of a bell crank lever 36. This lever is pivoted as at 37 to a stationary bracket 38 or other convenient part.

Pivoted to the other arm of the bell crank lever 36 is a locking pin 39 which passes through an arcuate slot 41 formed in a locking plate 42. This locking plate is carried by a hand lever 40 pivoted at 45 to the bracket 38 or other convenient part. The locking pin 39 is capable of vertical movement upon operation of the bell crank lever 36. Formed on the locking pin is a reduced portion or neck 43 which when the pin is in its lowest position, is accommodated by the arcuate slot 41 in the locking plate 42 so that the hand lever 40 may be then moved horizontally about its pivot 45 as hereinafter described. The slot 41 is provided with an enlarged or widened portion 44 (Figure 6) to receive the larger diameter of the locking pin 39 in which position the locking pin 90 prevents movement of the locking plate and hand lever 40 for the purposes hereinafter mentioned.

95 Associated with the abovementioned locking gear is exhaust valve controlling mechanism which may include a sliding member 100 or sleeve 49 mounted on the cam shaft 27 so as to be capable of axial movement relative thereto, this movement being effected synchronously with the movement of the locking plate 42 and hand lever 40 by means 105 of a projection 51 on said plate or lever, engaging flanged portions or collars 52 on the sliding sleeve 49. This sliding member also carries two cams 53 and 54 the former cam constituting the usual means of opening 110 the exhaust valve 55 at the beginning of the exhaust stroke while the second cam 54 constitutes an auxiliary means to open the exhaust valve during the compression stroke 115 when running on the starting mixture from the carburettor as before mentioned.

120 The cams 53 and 54 are mounted close together and are adapted to engage a roller 56 on a rocker arm 57 which operates the exhaust valve. Thus when the engine is being run on carburetted fuel in starting both cams intermittently actuate the rocker arm 57 so as to open the exhaust valve 55 during the compression as well as the exhaust stroke of the piston.

125 By moving the sleeve 49 axially along the cam shaft 27 the auxiliary cam 54 is dealigned from the roller 56 and rotates idly with the cam shaft. This sliding movement of the cams may only be effected when the 130

reduced portion of the locking pin 39 is in engagement with the arcuate slot 41 and the rotary fuel control valve 12 is consequently moved to cut off the carburettor from the cylinder. The exhaust cam 53 however still contacts with the roller 56 and causes the exhaust valve 55 to open in the usual manner during the exhaust stroke only.

The usual injection valve controlling the supply of the heavier oil fuel to the combustion chamber is indicated generally at 61 and the usual oil fuel and compressed air supply pipes leading respectively from the oil tank and injection air compressor to the valve 61 are indicated at 62 and 63 respectively. The injection valve is operated in the usual manner by a tappet rod 64 actuated by a cam 65 on the cam shaft.

To start an engine in accordance with the invention the air injection valve 61 may be rendered inoperative or the supply of oil fuel and compressed air to said valve cut off or other suitable means adopted to prevent admission of the normal working charge into the combustion chamber. The rotary fuel control valve 12 is then moved by hand operation of the connecting rod 34 or lever 36 into the position more clearly shown in Figures 4 and 5. This rotary movement of the valve in relation to the lever 36 being permitted by the flexible connections 33 and 35. In this position of the fuel control valve the gaseous starting mixture from the carburettor is admitted through the inlet branch 7 and port 13 into the interior of the valve casing 3 communication between the latter and the atmosphere being cut off by the valve 12 closing the air inlet port 11.

During the suction stroke of the engine carburetted air is now drawn past the inlet valve 16 into the combustion chamber wherein it is partially compressed as hereinafter described and eventually exploded by the spark plug 66 which may be connected to a magneto (not shown) operated from the cam shaft 27.

It should be particularly noted that when the fuel control valve 12 is in the above-mentioned position seen in Figures 4 and 5 the exhaust valve operating cams 53 and 54 carried by the sliding member 49 are both in position to intermittently actuate the exhaust valve rocker arm 57 and thereby open the exhaust valve 55 during both the compression and exhaust strokes of the piston. Thus a portion of the carburetted starting charge is discharged from the engine cylinder during the compression stroke and before firing takes place so that the compression is reduced to a sufficient extent to permit of safe combustion of the carburetted charge. It will also be noted that during such starting operations the exhaust operating cams 53 and 54 are locked against sliding movement on the cam shaft owing to the

major diameter of the locking pin 39 engaging the enlarged portion 44 of the slot 41 in the locking plate 42 as in Figures 1 to 3. It is thus impossible to move the auxiliary cam 54 out of action and thus obtain full compression until the fuel control valve 12 has been moved to cut off the carburettor and admit atmospheric air to the cylinder, this movement of the valve 12 causing the locking pin 39 to descend and release the cam shifting hand lever 40 as hereinafter described.

When the engine has gathered sufficient impetus the fuel control valve 12 is moved to the right in Figures 3 and 5 by manipulation of the connecting rod 34 or the bell crank lever 36 so that communication between the carburettor 9 and the interior of the valve casing 3 is thus cut off and the latter is opened to the atmosphere by port 14 of the valve registering with air inlet port 11 of the valve casing so that air only is drawn into the cylinder during the suction stroke. This movement of the bell crank lever and fuel control valve has the effect of forcing down the locking pin 39 so that the major diameter thereof is disengaged from the widened part 44 of the arcuate slot 41 and the reduced portion or neck 43 of the locking pin is engaged with said slot. The locking plate 42 may now be moved about its pivotal point 45 by the operating handle 40 to thereby cause the sliding member 49 to move along the cam shaft 27 to the right in Figures 1 and 2 so that the auxiliary or low compression cam 54 is removed from contact with the roller 56 of rocker arm 57 and the exhaust valve 55 is consequently opened during the exhaust stroke only by means of the exhaust cam 53.

The parts are now in position for normal working air only being drawn into the cylinder on the suction stroke and this air being fully compressed to afford the necessary heat for combustion of the heavier oil fuel. This fuel for normal working may now be supplied to and injected into the engine cylinder by the injection valve 61 in the usual manner so that the engine may operate on its normal cycle.

The ignition device or spark plug 66 which is provided only to ignite the starting charges, is rendered inoperative in any suitable manner on cutting off the supply of carburetted fuel and changing over to full compression as aforesaid.

It will be evident that various alterations, modifications and/or additions may be introduced into the particular construction of the apparatus herein described and illustrated without departing from the spirit and scope of the invention, which it will be seen, may be readily applied to existing engines and eliminates the necessity of the usual com-

pressed air starting apparatus, preheating elements and like starting devices.

Having now described my invention what I claim as new and desire to secure by Letters Patent is:—

1. Improvements in high compression oil engines consisting in the combination of means for supplying a starting charge of carburetted air fuel to the engine cylinder 10 on the suction stroke of the piston, valve mechanism adapted to release portion of said starting charge from the cylinder during the compression stroke thus reducing the degree of compression, means for manipulating said valve mechanism to thereby discontinue such reduction of compression after the engine has been started, a manually operated fuel control valve adapted to control the admission to the cylinder of said 20 carburetted fuel for starting purposes and admit atmospheric air for normal working, and a safety locking device operably connecting said fuel control valve with said manipulating means to thereby prevent operation of the latter to effect full compression until said fuel control valve has been moved to cut off the carburetted fuel supply and admit atmospheric air to the engine cylinder on the suction stroke of the piston 30 for the purpose specified.

2. Improvements in high compression oil engines consisting in the combination of means for supplying a starting charge of carburetted air fuel to the engine cylinder 35 on the suction stroke of the piston, an exhaust valve, an exhaust cam and an auxiliary cam adapted to open said valve during the exhaust stroke and compression stroke respectively, hand operated means to move 40 said auxiliary cam out of action when the engine has been started, a manually operated fuel control valve adapted to simultaneously cut off said carburetted fuel supply and admit atmospheric air to the cylinder 45 on the suction stroke of the piston, and a safety locking device interconnecting said fuel control valve with said hand operated means to thereby prevent said movement of the auxiliary cam until the fuel control 50 valve has been operated as aforesaid, for the purpose specified.

3. Improvements in high compression oil engines consisting in the combination of means for supplying a starting charge of carburetted air fuel to the engine cylinder 55 on the suction stroke of the piston, an exhaust valve, an auxiliary cam slidably mounted on a cam shaft and adapted to open said valve during the compression stroke 60 of the piston, a hand lever adapted to slide the auxiliary cam into an inoperative position when the engine has been started, a manually operated fuel control valve adapted to simultaneously cut off the carburetted fuel supply and admit atmospheric air to

the cylinder on the suction stroke of the engine, and a locking member operatively connected with said fuel control valve and adapted to prevent movement of said hand lever to render the auxiliary cam inoperative until the fuel control valve has been operated as aforesaid, for the purpose set forth.

4. Improvements in high compression oil engines consisting in the combination of means for supplying a starting charge of carburetted air fuel to the engine cylinder on the suction stroke of the piston, an exhaust valve, an auxiliary cam slidably mounted on a cam shaft and adapted to open said valve during the compression stroke of the piston, a hand lever adapted to slide the auxiliary cam into an inoperative position when the engine has been started, a locking plate carried by said hand lever and having an arcuate slot therein, a manually operated fuel control valve adapted to simultaneously cut off the carburetted fuel supply and admit atmospheric air to the cylinder on the suction stroke of the engine, and a locking pin operatively connected with said fuel control valve and adapted to engage said arcuate slot of the locking plate whereby the hand lever is locked against movement to render the auxiliary cam inoperative until the fuel control valve has been operated as aforesaid for the purpose specified.

5. Improvements in high compression oil engines consisting in the combination of means for supplying a starting charge of carburetted air fuel to the engine cylinder on the suction stroke of the piston, an exhaust valve, an auxiliary cam slidably mounted on a cam shaft and adapted to open said valve during the compression stroke of the piston, a hand lever adapted to slide the auxiliary cam into an inoperative position when the engine has been started, a locking plate carried by said hand lever and having an arcuate slot therein, a manually operated fuel control valve adapted to simultaneously cut off the carburetted fuel supply and admit atmospheric air to the cylinder on the suction stroke of the engine, and a locking pin operatively connected with said fuel control valve, said locking pin having a reduced portion adapted to engage said slot of the locking plate to permit movement of the hand lever to render the auxiliary cam inoperative, the major diameter of said locking pin being adapted to engage an enlarged portion of said slot to thereby prevent such movement of the hand lever until the fuel control valve has been operated as aforesaid and the reduced portion of the locking pin is consequently engaged with said slot for the purpose specified.

6. Improvements in high compression oil engines consisting in the combination of

- means for supplying a starting charge of carburetted air fuel to the engine cylinder on the suction stroke of the piston, an exhaust valve, an auxiliary cam slidably 5 mounted on a cam shaft and adapted to open said valve during the compression stroke of the piston, a hand lever adapted to slide the auxiliary cam into an inoperative position when the engine has been started, a manually 10 operated rotary fuel control valve adapted to simultaneously cut off the carburetted fuel supply and admit atmospheric air to the cylinder on the suction stroke of the engine, a connecting rod attached at one 15 end to said fuel control valve, a bell crank lever attached to the other end of said rod, a locking pin depending from said lever, said locking pin having a reduced portion adapted to engage said slot of the locking 20 plate to permit movement of the hand lever to render the auxiliary cam inoperative, the major diameter of said locking pin being adapted to engage an enlarged portion of said slot to thereby prevent such movement 25 of the hand lever until the rotary fuel control valve has been operated as aforesaid and the reduced portion of the locking pin is consequently engaged with said slot for the purpose specified.
- 30 7. Improvements in high compression oil engines consisting in the combination of a carburettor, a cylindrical valve casing in communication with said carburettor and the engine cylinder, a manually operable 35 rotary fuel control valve mounted within said casing and adapted to simultaneously cut off communication with the carburettor and open the cylinder to the atmosphere during the suction stroke of the piston, an 40 exhaust valve operating mechanism adapted to open said exhaust valve during both the compression and exhaust strokes of the engine during starting operations, a hand lever
- associated with said valve operating mechanism and adapted for movement to render 45 the exhaust valve inoperative during the compression stroke after the engine has been started, and a safety locking device connected with said rotary fuel control valve and adapted to prevent said movement of the 50 hand lever until the fuel control valve has been moved to cut off the carburetted fuel supply and open the cylinder to the atmosphere on the suction stroke of the piston for the purpose set forth.
- 55 8. Improvements in high compression oil engines consisting in the combination of means for supplying a starting charge of carburetted air fuel to the engine cylinder, of inlet and exhaust valves operated from a cam shaft, a manually operated fuel control valve adapted to control the admission to the engine cylinder of carburetted fuel for starting and atmospheric air for normal working by way of said inlet valve during 60 the suction stroke of the piston, a pair of alternately operating cams slidably mounted on said cam shaft and adapted to open the exhaust valve on both the exhaust and compression strokes of the piston during starting operations, a hand lever adapted to slide said cams along the cam shaft to thereby render one of the cams inoperative and discontinue the opening of the exhaust valve on the compression stroke after the engine 65 has been started and a safety locking device operatively associated with said fuel control valve and the hand lever to prevent said movement of the latter until the fuel control valve has been moved to a pre-determined 70 position for the purpose specified.
- 75 In testimony whereof I affix my signature.

T. A. BELL.

Witness:

VICTOR J. KELSEY.
